W. J. KENNEDY,
VALVE FOR GAS STOVES.
APPLICATION, FILED FEB. 12, 1920.

1,425,975.

Patented Aug. 15, 1922.

UNITED STATES PATENT OFFICE.

WALTER J. KENNEDY, OF CLEVELAND, OHIO.

VALVE FOR GAS STOVES.

1,425,975.

Specification of Letters Patent. Patented Aug. 15, 1922.

Application filed February 12, 1920. Serial No. 358,246.

To all whom it may concern:

Be it known that I, WALTER J. KENNEDY, a citizen of the United States, and resident of Cleveland, in the county of Cuyahoga and State of Ohio, have invented certain new and useful Improvements in Valves for Gas Stoves, of which I hereby declare the following to be a full, clear, and exact description, such as will enable others skilled 5 in the art to which it appertains to make and use the same.

The objects of the invention are to provide simple and efficient mechanism for operating the valve of the gas or gasoline burner of a cook stove, to turn on the gas, said mechanism actuated by the agency of the cooking utensil as it is put upon the grating or cover over the burner. This mechanism is also designed to operate automatically to close the valve and shut off the gas when the cooking utensil is removed.

A further object of the invention is to provide valve operating mechanism, which can not only be actuated by the agency of the cooking utensil when placed upon the stove but which is so constructed that it can be operated at any time by hand in the manner of an ordinary valve, if so desired.

The invention includes a spring pressed movable valve operating member, and a horizontally movable arm, which projects over the stove grating or cover, and which is moved by the action of a cooking utensil when placed upon the stove. This arm is operatively connected with the spring which retains the valve and valve operating member in the closed position, and a releasing spring opens the valve when the pressure thereon is removed.

It includes a separate controlling means for the valve operating member, permitting the operation of the valve independently of the aforesaid arm, and also serving as a means for positively controlling the movements of said valve and arm.

In the accompanying drawings Fig. 1 is a plan of a gas stove showing the improved burners. Fig. 2 is a vertical central section of one of the burners; Fig. 3 is a plan thereof; Fig. 4 is a perspective of the valve

closing spring. Fig. 5 is a vertical central section of a modified form of valve; Fig. 6 is a detail section of the valve for the pilot light.

In these views A, is the vertical body or casing of the burner valve, B is a needle valve and C is the valve seat which is longitudinally movable in the horizontal passage D in the valve casing, to regulate the amount of pressure of the gas. E is an elbow shaped member to which the valve is attached. This member E, moves horizontally or laterally of the vertical portion of the casing, and the horizontal arm F, moves 60 slidingly in the horizontal opening G, in a screw threaded controlling stem H, movable in a projection I upon the casing opposite the valve and above the manifold Z which supplies gas to all the burners of the 70 stove. The part F of the valve support E being raised above the manifold Z, can be adjusted through the casing instead of through the manifold Z which would be necessary if the support were entirely horizontal and was passed out directly through the manifold. The construction for this reason prevents making an opening through the manifold for the adjusting member A to pass through. Its movements are limited 80 by means of the pin J, positioned in the opening K in the arm F. The amount of the movement of the valve is regulated by means of this stem.

The valve is normally held in the closed 85 position by means of the flat spring M, shown in Figs. 2 and 4, which is adjustably pressed against the valve supporting member E, by means of the screw plug N, O is a fulcrum pin over which the spring is bent 90 to provide the required pressure. The spring M is slotted at P to permit it to straddle the elbow shaped valve support.

At Q is shown an arm which extends over the stove grate or cover and which is moved aside as the kitchen utensil is put upon the stove. This arm rotates the vertical pin or stem R, in the casing A, and at its lower end the eccentric projection S engages the flat spring M and moves it back to free the 100 valve support F from its pressure. Immediately the releasing spring T pushes back

the valve and permits the gas to flow, the amount of pressure and the flow of gas being controlled by means of the screw stem previously described. When the cooking utensil is removed, the action of the flat spring M, will return the arm to its normal position, permitting the flat spring, the pressure of which is greater than that of the releasing spring, to close the valve. A pilot light is, of course, necessarily burning from the feed pipe, V, and is controlled by means of the valve W.

In Fig. 2, the valve is shown adapted to control the pressure of the gas, before it enters the mixer. In Fig. 5 a simple valve is shown an additional regulator X, must be used, or it must be proportioned for a predetermined pressure.

The above described valve can be operated in either of two ways; first, automatically by means of the horizontal arm Q. This arm can be moved accidentally or intentionally beyond the valve closing position without causing any damage to the parts or additional flow of gas because the spring M will permit it to revolve at will. This makes the device safe for general use. Second, the valve can be controlled wholly by means of the stem H, by means of which, and the transverse pin J, the valve can be opened by hand if the arm Q should become broken.

It is understood that the utensil is employed as an implement to move the valve arm from one side to the other but may be often placed directly upon the arm by accident.

This is more likely to occur since in applicant's former Patents Nos. 1,217,955; 1,190,656; 1,144,209; the valve was operated in this manner and anyone accustomed to the use of the former valve would be more than likely to do so again.

For this reason the valve operating arm Q, is constructed of thin spring metal so that it will not become bent or broken.

Having described the invention what I claim as new and desire to secure by Letters Patent is:

1. The combination with the inlet valve of a gas stove burner, and valve casing therefor, of a swinging arm movable horizontally over said stove, and pivoted in said valve casing and means operatively connecting said arm and valve for opening said valve when said arm is swung upon its pivot.

2. The combination with the inlet valve of a gas stove burner, and valve casing therefor, of a swinging arm movable horizontally over said stove, and pivoted in said valve casing, and means operatively connecting said arm and valve for opening said valve when said arm is swung upon its pivot, and automatically acting means for returning said valve and arm to their former positions.

3. In a valve for the burner of a gas

stove in combination, a valve and casing therefor, a spring for normally closing said valve, a swinging arm horizontally movable over said stove and pivoted in said casing, and means on said arm for engaging said spring, to withdraw said spring when said arm is swung upon its pivot; said spring serving to return said valve and arm to their original positions when said arm is released.

4. In a valve for the burner of a gas stove, in combination, a valve and casing therefor, a spring for normally closing said valve, a swinging arm horizontally movable over said stove and pivoted in said casing, and means on said arm for engaging said spring to withdraw said spring when said arm is swung on its pivot, a spring for opening said valve when said first mentioned spring is withdrawn, said first mentioned spring serving to close said valve and to return said arm to its original position when said arm is released.

5. In a device for controlling the flow of gas to a gas stove burner, in combination, an inlet passage leading to the burner, a movable closure for controlling the flow of gas through said inlet passage and a swinging arm movable horizontally over said stove and burner and operatively connected with said closure.

6. In a valve for a gas stove burner in combination, a casing, a valve horizontally movable therein, a seat therefor, a supporting member for said valve, a spring engaging said valve support for normally closing said valve on said seat, a horizontally swinging arm, a pivot therefor in said casing, engaging means on the pivot of said arm, for said spring, engaging means operating to withdraw said spring when said arm is moved from its normal position, a releasing means for said valve, and support, and adjustable means for controlling the amount of movement of said valve and support, independently of the movement of said arm.

7. In a valve for the burner of a gas stove, in combination, a valve and casing, a supporting member for said valve in said casing, a spring for normally closing said valve, a screw threaded stem, a projection from said valve support longitudinally movable in said stem, and means for limiting the movements of said projection in said stem.

8. In a device for controlling the flow of gas to a gas-stove burner, in combination, an inlet passage leading to the burner, a movable closure for controlling the flow of gas through said passage, a spring for normally retaining said closure in closed position, a swinging arm engaging means operatively connected with said swinging arm for withdrawing said spring, and a releasing spring constructed to remove said closure, when the first mentioned spring is withdrawn.

9. The combination with a valve for the

burner of a gas stove, and valve casing therefor, of a yielding horizontally swinging arm movable horizontally over said stove, and pivoted in said valve casing and
5 means operatively connecting said arm, and valve for opening said valve when said arm is swung upon its pivot.

In testimony whereof, I hereunto set my hand this 10th day of February, 1920.

WALTER J. KENNEDY.
